UNITED STATES PATENT OFFICE.

WILLIAM H. GRAHAM, ST. LOUIS, MISSOURI.

DESIGN FOR A SEWER-TRAP.

SPECIFICATION forming part of Design No. 18,981, dated April 2, 1889.

Application filed September 8, 1888. Serial No. 284,936. Term of patent 14 years.

To all whom it may concern:

Be it known that I, WILLIAM H. GRAHAM, a citizen of the United States, residing at St. Louis, in the State of Missouri, have invented and produced a new and original Design for a Sewer-Trap for Basins and the Like, of which the following is a specification, reference being had to the accompanying photograph, forming part hereof, which photograph shows a side elevation of my design.

The leading features of the design are a bulbous expansion formed in the down-leg of the **U** part of the trap, an acorn-shaped tap-nut at the lower part of said bulb, and curved ventilator and delivery pipes connected with the up-leg of the trap by chamfered nuts.

1 is the straight portion of the trap, which is adapted to be connected with the discharge-pipe of the basin.

2 is a bulbous expansion forming the down-leg of the **U** part of the trap.

3 is a tap-nut of acorn shape, so as to add symmetry and grace to the curves and proportions of the design.

4 is the straight horizontal part of the trap, and is connected with the delivery-pipe by curved and downward extension 5.

6 is a nut that covers the joint between the parts 4 and 5.

7 is a ventilating-pipe, curved as shown, and joined to the trap by a nut, 8. These nuts 6 and 8 are chamfered off at the points 10 and 11, so as to harmonize with the rest of the trap and make a more beautiful design.

9 is the up-leg of the trap.

The trap is to be used for exposed work—that is, where the basin is not boxed in.

The part 2 is expanded gradually into a pronounced bulb and joined to the parts of 1 and 9 by gentle and symmetrical curves.

What I claim is—

The design for sewer-traps, substantially as herein shown and described, the same comprising the part 1, the bulb 2, having acorn-shaped tap-nut 3 at the end of said bulb, the straight pipe 4, the up-leg 9 of the **U** part of the trap, the curved delivery-pipe 5, and the curved ventilator 7, having the chamfered nuts, as described.

In testimony whereof I have hereunto set my hand and affixed my seal, this 24th day of August, 1888, in the presence of the two subscribing witnesses.

WILLIAM H. GRAHAM. [L. S.]
